UNITED STATES PATENT OFFICE.

WALTER J. JEFFRIES AND RUFUS H. MACKENZIE, OF BELLINGHAM, WASHINGTON.

DESIGN FOR AN ENGAGEMENT RING.

Application filed April 17, 1926. Serial No. 17,333. Term of patent 3½ years.

To all whom it may concern:

Be it known that we, WALTER J. JEFFRIES and RUFUS H. MACKENZIE, citizens of the United States, residing at Bellingham, in the county of Whatcom and State of Washington, have invented a new, original, and ornamental Design for Engagement Rings, of which the following is a specification, reference being had to the accompanying drawing, forming part thereof.

Figure 1 is a side elevation of an engagement ring showing our design; and Fig. 2 is an edge elevation of the same.

We claim:

The ornamental design for an engagement ring, as shown.

In witness whereof, we hereto subscribe our names this 9th day of April A. D. 1926.

WALTER J. JEFFRIES.
RUFUS H. MACKENZIE.
